UNITED STATES PATENT OFFICE

106,669

DESIGN FOR AN AUTOMOBILE DIRECTION SIGNAL

Russell T. Huff, Catlettsburg, Ky.

Application August 18, 1937, Serial No. 71,183

Term of patent 7 years

To all whom it may concern:

Be it known that I, Russell T. Huff, a citizen of the United States, residing at Catlettsburg, in the county of Boyd and State of Kentucky, have invented a new, original, and ornamental Design for an Automobile Direction Signal, of which the following is a specification, reference being had to the accompanying drawing, forming part thereof.

Figure 1 is a view in front elevation of an automobile direction signal, showing my new design.

Figure 2 is a view in side elevation thereof.

I claim:—

The ornamental design for an automobile direction signal as shown.

RUSSELL T. HUFF.
